WILLIAM H. BAKER, OF CENTRAL FALLS, RHODE ISLAND, AND FREDERIC E. KIP, OF MONTCLAIR, NEW JERSEY.

AUTOMATIC CONTROLLING MECHANISM FOR LOOMS.

SPECIFICATION forming part of Letters Patent No. 655,646, dated August 7, 1900.

Application filed January 5, 1900. Serial No. 410. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Automatic Controlling Mechanisms for Looms, of which the following is a specification.

10 This invention relates to mechanical devices for indicating the exhaustion or substantial exhaustion of the weft or filling in the weft-carrier or shuttle in play in a loom for automatically controlling or setting in motion mechanism for furnishing a fresh supply of weft or filling or for stopping the loom, so that a supply of weft or filling may be furnished; and in the present invention the object is to provide within the weft-carrier 15 means whereby when the weft or filling in the carrier or shuttle is substantially exhausted the fact will be indicated by the periodical entry of a feeler into the shuttle, and if the weft is nearly or quite exhausted, as the case 20 may be, mechanism will be set in motion to furnish a fresh supply or to stop the loom.

In the drawings which serve to illustrate the invention, Figure 1 is a longitudinal vertical axial section of a shuttle and an exhausted bobbin or weft-holder therein, illustrating the invention; and Fig. 2 is a plan of the left-hand end of the same, showing the feeler. Fig. 3 is a fragmentary section of the bobbin of Fig. 1, but on a larger scale and showing weft or filling on the bobbin. Fig. 4 is a sectional view similar to Fig. 1, but showing a spindle in the shuttle and a full bobbin thereon. Fig. 5 illustrates the invention as applied to a bobbin or weft-holder 25 mounted in a bobbin-ease, which latter is to be mounted in a shuttle. Fig. 6 is a view similar to Fig. 1, but illustrating a construction wherein the feeler instead of normally impinging on the indicator-arm of the bobbin is adapted to so impinge only when the weft or filling in the shuttle is substantially exhausted. Fig. 7 is a sectional view showing the bobbin on the spindle of a winding-frame and illustrating a feature which will 30 be hereinafter described.

Referring primarily to Figs. 1, 2, and 3, a

represents a shuttle open at top and bottom and having two spring-jaws *b b* to embrace and hold the bobbin *c* in place. To receive the jaws, the bobbin has about its butt a circumferentially-grooved ring *d* where the jaws embrace it. The butt or enlarged end of the bobbin has in it a longitudinally-extending slot, in which is mounted an indicating-lever *e*, fulcrumed at *f* in or on a ring embracing 55 the bobbin. A spring *g* bears at its free end on the inner face of the lever *e* and tends to press it outward against the ring *d* or other stop, and when the weft or filling carried by the bobbin is substantially exhausted said lever will be so pressed outward, as seen in Fig. 1. The lever is curved and its arched portion protruded from the slot when pressed outward, as in Fig. 1; but when the yarn or filling *h* is wound on the holder *c*, as seen in 60 Fig. 3, it overwraps the lever *e* and prevents it from protruding, so that the free end of the lever is held pressed in and out of contact with its stop.

Some part of the lever *e*, and preferably 65 its free extremity, which extends beyond the ring *d*, forms the detent-indicator, which by the movement in or out radially of the lever *e* either places itself in the path of a feeler *i* or moves out of said path. The feeler *i* (seen 70 in Fig. 2) is a known device and will need no further description here than the statement that as ordinarily constructed said feeler enters the shuttle when the lay beats up and serves to control the weft-supplying or stopping mechanism of the loom. Where the indicator-lever is normally in its path, the feeler will be pressed backward and actuated to avoid the operation of other mechanism on the loom. It will not be necessary to 75 describe such mechanism, as it is known and operated on looms now in use. As shown in Figs. 1, 2, and 3, the free end of the indicator-lever *e* when the latter is held pressed in by the yarn or filling *h* on the bobbin projects just above the surface of the bobbin 80 and in the path of the feeler *i*, which plays over the top of the bobbin at this point, so that at each vibration of the lay under normal conditions the feeler enters the shuttle 85 and impinges on said lever; but when the yarn *h* is substantially exhausted and a fresh 90

supply is required the spring *g* is permitted to press the lever *e* outward, so that the detent-head of the same is moved outward and above the path of the feeler *e*. Consequently 5 the latter will not be actuated and the weft-supplying or loom-stopping mechanism controlled thereby will be actuated.

It will be understood that the shuttle *a* will be cut down at one side or provided with an 10 aperture in its side to permit the feeler *i* to enter, and if there be a bobbin-case *j* in the shuttle, as seen in Fig. 5, this case will also be provided with a recess or aperture coincident with that in the shuttle for the entry 15 of the feeler.

Fig. 4 shows the same construction as that seen in Fig. 1, except that the shuttle has in it a spindle *k* to hold the bobbin. In an automatic weft-supplying mechanism employing 20 the construction of Fig. 1 the exhausted bobbin is knocked out and replaced by a full one. In the construction of Fig. 5 the bobbin-case is knocked out, and in the construction shown in Fig. 4 the shuttle will be displaced. 25

Fig. 6 shows a view illustrating the construction shown in Fig. 1, except that the detent-head *l* of the lever *e* is adapted to be held by the weft on the bobbin under normal 30 conditions out of the path of the feeler *i* and to be put into the path of the said feeler by the spring *g* when the weft or filling is substantially exhausted.

It will be understood that the ring or band 35 *d* on the bobbin is only a convenience for providing a surface for the jaws *b* to bear on, and any means may be employed for this purpose. Incidentally the ring *d* serves as a stop to limit the movement outward of the 40 lever *e*. These details may be varied without departing in any way from our invention.

It will be noted that the indicator-lever *e* has a short arm or heel *m* back of the fulcrum *f* and that this arm or heel *m* protrudes 45 into the hollow or bore in the bobbin when the bobbin is empty or exhausted of weft, as seen in Fig. 1. The object of this will be explained. It is found that in winding a bobbin having an indicator-lever of this character that the centrifugal force acting to throw or force said lever outward radially is greater than the yarn can overcome in winding on or overwrapping it. Therefore the arm or heel *m* is made to project into the path of the 50 spindle of the winding-frame, so that when the bobbin is slipped onto said spindle the latter will displace said arm *m* outward, and thus draw in and hold in the lever *e*, so that the centrifugal force cannot act on it. In 55 Fig. 7, which shows a bobbin *c* on the spindle *n* of a winding-frame or spinning-frame, it will be noted how the said spindle displaces the arm *m*. When there is a spindle

in the weft-carrier to receive the bobbin, as in Fig. 4, for example, there will be a recess 65 *o* in said spindle coincident with the arm or heel *m*, so as to permit the lever *e* to move outward when the weft or filling is nearly or quite exhausted.

The word "bobbin" as herein employed is 70 meant to include any one of the various forms of weft or filling holders employed in weaving.

It may be stated that a feeler operating on the principle illustrated in Fig. 6—that is to say, adapted to miss the indicator in the shuttle normally or when there is a supply of weft in the carrier and to impinge upon it when the weft is substantially exhausted—is illustrated in our pending application, Serial No. 4,221, filed February 6, 1900. 80

Having thus described our invention, we claim—

1. A bobbin or weft-holder having in it a longitudinal slot, an indicator-lever provided with a detent-head and fulcrumed in said slot, a stop on said weft-holder to limit the outward movement of the detent-head on the lever, and a spring behind said lever and adapted to move the latter out to said stop, said lever having a projecting portion overwrapped by the weft and the detent-head on the lever being thus depressed and held out of the path of a feeler. 85

2. A bobbin or weft-holder having a longitudinal slot and having in said slot a radially-movable indicator-lever backed by a spring which tends to move it outward and up to a stop, and the said spring, said lever having a curved or arched portion adapted to be overwrapped by the weft and a detent-head adapted to be put into and out of the path of a feeler, the weft on the bobbin holding it in one of its positions and the said spring holding it in its other position. 95

3. The combination with a shuttle having 105 means for holding the bobbin in place therein, and adapted to permit the entry of a feeler, of a bobbin to fit into said shuttle and provided with a longitudinal slot, an indicator-lever fulcrumed in said slot, and having an arched portion to be overwrapped by the weft or filling, a heel which is adapted to project into the hollow of the bobbin when the latter is exhausted of weft, and a detent-head, adapted to be put into and out of the 110 path of the feeler, and a spring adapted to hold said indicator-lever in one of its two positions. 115

In witness whereof we have hereunto signed our names, this 13th day of December, 1899, in the presence of two subscribing witnesses. 120
